(57) CLAIM

The ornamental design for a flood light shroud, substantially as shown and described.

DESCRIPTION

FIG. 1 is a top perspective view of a flood light shroud showing my new design.

FIG. 2 is a bottom plan view thereof. The top side of the flood light shroud is symmetrical to the bottom side.

FIG. 3 is a right side elevational view thereof. The left side of the translucent roof vent is symmetrical to the right side.

FIG. 4 is a top perspective view of an alternate embodiment of a flood light shroud, embodying my design.

FIG. 5, is a bottom plan view thereof. The top side of the flood light shroud is symmetrical to the bottom side; and, FIG. 6 is a right side elevational view thereof. The left side of the translucent roof vent is symmetrical to the right side.
